PROCESS FOR THE PRODUCTION OF OIL
OF LOW MOBILITY

Ronald L. Reed, Allison Park, Paul L. Terwilliger, Oakmont, and Lawrence A. Wilson, Jr., Unity, Pa., assignors to Gulf Research & Development Company, Pittsburgh, Pa., a corporation of Delaware

Filed May 21, 1962, Ser. No. 196,293
6 Claims. (Cl. 166—11)

This invention relates to the production of oil from underground oil-bearing formations and more particularly to the production of oil having a low mobility at the conditions normally existing in an oil-bearing formation.

Vast quantities of oil which are not susceptible to recovery by conventional production techniques exist in known deposits frequently referred to as tar sands. Economical production of oil from such formations by the conventional primary or secondary techniques is prevented by the high viscosity or high pour point of the oil at the reservoir conditions which makes the oil substantially immobile.

A secondary recovery technique that has been suggested for the recovery of highly viscous oils is the in-situ combustion process in which an oxygen-containing gas is injected into the formation and oil in the formation is ignited to cause combustion of oil in place in the subsurface formation. A principal purpose of the in-situ combustion process is to raise the temperature of the oil-bearing formation high enough for the oil to become mobile and flow to a well. Production is further increased by the products of combustion displacing some of the oil from the formation.

One of the in-situ combustion processes that has been suggested is the forward burning process in which oil in the subsurface formation is ignited adjacent an injection well used to supply an oxygen-containing gas, usually air, for the combustion. In the forward burning process the oxygen-containing gas and the combustion front move in the same direction. Forward burning is not an effective means for the recovery of oils of low mobility from subsurface formations because a bank of fluid oil, gas, and water immediately ahead of the combustion front is prevented from flowing to the production well by the highly viscous cold oil surrounding the production well. The blocking of the flow of oil to the production well prohibits injection of oxygen-containing gas into the oil-bearing formation at a rate high enough to maintain combustion.

Another in-situ combustion method that has been suggested for use in recovery of heavy oils is reverse combustion. In reverse combustion processes, an oxygen-containing gas is displaced down an injection well and into the oil-bearing formation. Oil in the formation adjacent the production well is heated to a temperature at which the oil will ignite when contacted with air traveling toward the production well from the injection well. Continued displacement of the oxygen-containing gas into the oil-bearing formation causes the combustion front to move toward the injection well, countercurrent to the flow of gas. In the reverse combustion process, the underground formation downstream from the combustion front is hot; hence the oil flows readily to the production well. However, if the underground formation has a very low permeability, it may not be possible to displace the oxygen-containing gas through the formation to the combustion front at a high enough rate to maintain combustion. Moreover, low temperature oxidation between the injection well and the combustion front consumes much of the oxygen and may cause little oxygen to reach the combustion front. Reverse combustion has

2

the further disadvantage of causing a substantial portion of the oil present in the formation to remain unrecoverable in the formation as coke.

This invention resides in a novel in-situ combustion process for the recovery of oils of low mobility from an underground oil-bearing formation penetrated by an injection well and a production well spaced from the injection well. Initially, a narrow hot streak of substantial permeability extending through the oil-bearing formation from the injection well to the production well is created. The hot streak includes a fracture extending substantially horizontally from the production well propped open to form a channel of high flow capacity and an unproped fracture extending from the injection well toward the production well. Both fractures are heated prior to ignition of the oil in the formation to provide the hot streak connecting the wells. An oxygen-containing gas is injected into the fracture at the injection well and oil in the formation is ignited adjacent the injection well. Continued injection of the oxygen-containing gas causes burning of oil in the formation and flow of heated oil through the hot streak to the production well and heating of the subsurface formation whereby the fracture communicating with the injection well closes behind the combustion front.

In the drawings:

FIGURE 1 is a diagrammatic view in vertical section of an injection well and a production well as equipped for heating the fracture extending from the injection well and with tubing for delivery of oil from the production well;

FIGURE 2 is a diagrammatic view, partially in vertical section, illustrating the progress of the heated zone through the oil-bearing formation during the recovery of oil in the process of this invention; and

FIGURE 3 is a plan view of a five-spot arrangement of wells with the limits of idealized fractures indicated by broken lines.

Referring to FIGURE 1 of the drawings, an underground oil-bearing formation 10 is shown penetrated by an injection well 12 and a production well 14. The oil in oil-bearing formation 10 should have a low mobility at reservoir conditions and must have a substantial change in viscosity with a moderate change in temperature. The term "low mobility" refers to mobilities less than one when the mobility is the ratio of the permeability of the formation in millidarcys to the viscosity of the oil at reservoir temperature in centipoises. Oils capable of the substantial change in viscosity essential to the process of this invention with a moderate change in temperature have a viscosity exceeding 50 centipoises at reservoir conditions. The low mobility of the oil can be caused by a high pour point of the oil or by the presence of highly viscous bituminous material in the oil. Oil-bearing formations suitable for treatment in accordance with this invention are frequently referred to as tar sands, rock asphalt, bituminous sands, and bituminous rock. For convenience, formation 10 is hereinafter referred to as a tar sand; however, it is to be understood that the term is used in a generic sense to include any of the formations listed in the preceding sentence containing an oil of low mobility as defined above.

After the injection well 12 is drilled through the tar sand 10 into base rock 16, casing 18 is run into the well and cemented in place by any conventional cementing technique. In FIGURE 1, well 12 is illustrated with a burner 20 supported in the borehole a short distance above the lower boundary of the tar sand at the lower end of a fuel supply line 22 which extends down the well within tubing 24. The fuel line 22 is connected at its upper end to a fuel supply line 26. An air supply line 28 is connected into the tubing 24 at the well head.

Burner 20, which is illustrated diagrammatically, is provided with suitable openings for admixture of air delivered through the annulus between fuel line 22 and tubing 24 with the fuel delivered through line 22. A suitable burner is described in Patent No. 2,668,592 of Piros. Well 12 is also provided with a side outlet 30 at the upper end of the casing for the introduction of a suitable diluent into the casing to provide temperature control in the manner hereinafter described.

Production well 14 is spaced from the injection well 12 in accordance with the plan for developing the oil field. A suitable arrangement is a five-spot pattern such as is illustrated in FIGURE 3 in which production wells 14(a), 14(b), 14(c), and 14(d) are spaced around an injection well 12. The arrangement of wells illustrated may be part of a series of repeated five-spot patterns. Of course, arrangements of injection and production wells other than the five-spot arrangement illustrated in FIGURE 3 can be used. The particular arrangement and spacing of the wells used will depend upon the characteristics of the tar sand 10 and the plans for development of the oil field.

Production well 14 has casing 32 extending through the tar sand 10 to the base rock 16. Casing 32 may be cemented in place in accordance with conventional techniques for setting casing. Extending down through casing 32 is production tubing 34 which opens at its lower end within the casing near the bottom of the tar sand 10. Production tubing 34 extends up through a cap 36 at the upper end of the casing for delivery of production from the well. If desirable, a pump can be installed in tubing 34 to lift oil from well 14.

After casing 32 is set in production well 14, a substantially horizontal fracture 42 is made to extend from each of the production wells 14 into tar sand 10 near the bottom boundary thereof. The fracture is preferably created by cutting an opening in the casing 32 at the desired location of the fracture and cutting a horizontal notch in the tar sand 10 to fix the location and plane of the fracture. A fracturing fluid such as an oleaginous or aqueous liquid, which may or may not contain a thickening agent, is then pumped down the well and the pressure on the fracturing fluid increased to overcome the pressure of the overburden and the tensile strength of the tar sand 10. After the fracture is created, as indicated by a drop in the pressure on the fracturing fluid, additional fracturing fluid is pumped into the fracture to extend it a desired distance from the well 14. A liquid containing a heat-resistant propping agent is then displaced into the fracture to provide a fracture having a fluid flow capacity several times the capacity of the tar sand 10 prior to fracturing. A preferred propping agent is 4 to 8 mesh sand. It is preferred that the fracture 42 extend at least about 20 to 30 percent of the distance to the injection well 12. A suitable process for creating the fracture is described in Patent No. 2,699,212 of Newton B. Dismukes. The process described in that patent for the creation of a vertical fracture can readily be modified to create the desired horizontal fracture 42 by initially cutting a horizontal notch in the borehole wall.

When a five-spot arrangement of the type illustrated in FIGURE 3 is employed, a fracture 42 is created at each of the production wells 14(a), 14(b), 14(c), and 14(d). The extent of the fractures extending from the production wells is indicated diagrammatically in FIGURE 3 by the broken lines 42(a), 42(b), 42(c), and 42(d).

After the creation of the fractures 42 extending from each of the production wells, the surfaces of the fractures and a narrow zone of the tar sand within about three feet above and below the fractures are rapidly heated by passing a hot gas through the fracture. For this purpose, a burner, which may be of the type illustrated in FIGURE 1 in the injection well 12, is located in the production well 14 opposite the fracture 42, and the products

of combustion from the burner are passed outwardly through the fractures. The heating of the fractures is continued until the portion of the tar sand within approximately three feet of the fracture is heated to a temperature in the range of 400° to 700° F. for a distance of 20 to 30 percent of the distance from the production well to the injection well.

It is important to restrict the heating to a narrow zone adjacent the surfaces of the fracture; otherwise the amount of heat required to raise the tar sand adjacent the fracture to the desired temperature is excessive, a long time is required to supply the large amount of heat required, and the heat lost to the surrounding formation is large. Heating of the formation above the fracture renders oil present in that portion of the tar sand fluid and results in migration of hot gases injected into fracture 42 upwardly into the formation. Such migration encourages the creation of a fracture at an upper level in the tar sand. Heating of the tar sand 10 above the fracture can be prevented by circulation of a cooling fluid such as inert gases, air, or water down the annulus surrounding the burner. The cooling fluid further provides control of the maximum temperature of the combustion products entering the fracture 42 to a temperature in the range of 400° to 1200° F., and preferably from 400° to 700° F.

The exact gas rate and injection gas temperatures used to heat the tar sand adjacent fracture 42 will be different for each reservoir and well spacing, but it is important that the tar sand within one to three feet of the fracture be heated to the desired temperature in a period of one to three weeks. The minimum rate of injection of hot gases at a temperature within the limits of 400° F. to 1200° F. to accomplish the desired heating can be calculated from the formula $Q=155L^2$ when Q is the gas injection rate in standard cubic feet per day and L is the distance in feet between the injection and production wells. In a five-spot pattern with a well spacing of 250 feet between production wells, the injection of a gas at a temperature of 675° F. at a rate of 10,000,000 std. cu. ft. per day into the fracture will heat the tar sand for a distance of three feet on either side of the fracture to a temperature of 400° F. for a distance of about 60 feet from the production well in approximately 14 days. If the rate of flow of the gases is reduced to 1,000,000 std. cu. ft. per day, approximately one year is required before the desired heat distribution along the fracture is obtained.

A preferred method of obtaining the desired heating of the tar sand adjacent the fractures communicating with the production well in a five-spot pattern is to circulate the hot combustion products from one production well to another. For example, referring to FIGURE 3 of the drawings, a burner can be installed in each of wells 14(a) and (14d). Hot combustion products are displaced at the rates and temperatures mentioned above into the fractures communicating with those wells and discharged through wells 14(c) and 14(b). After the fractures adjacent the wells 14(a) and 14(d) have acquired the desired temperature distribution, burners can be installed in wells 14(c) and 14(b) and the hot combustion products from those burners vented through wells 14(a) and 14(d). In formations of low effective permeability to gas, it may not be possible to cause the high gas volumes required for the heating step to flow from one production well to another at normal injection pressures. In such instances, the injection pressure on the hot gases can be increased until the propped fracture is pneumatically extended from one production well to another. After the heating has been completed and the injection pressure released, the pneumatically extended fracture will close and leave only the propped portion of the fracture open. After heating of the fracture 42 has been completed, the burner is pulled from the production wells 14, and the production tubing 34 is run through

the fracture. Casing 32 may be perforated at 43 through the tar sand 10 before lowering the tubing.

A substantially horizontal fracture 44 is created from the injection well 12, preferably by notching the formation at the desired depth in the injection well 12 and then displacing a fracturing fluid free of propping agent down the injection well under a pressure adequate to create a fracture. Fracture 44 is extended at least about 80 percent of the distance to the production well 14. The fracture 44 should be located at a depth near the lower boundary of tar sand 10 such that fracture 44 will be close to fracture 42 whereby, during the subsequent heating step, a narrow hot zone extending from the injection well to the production well is created in the tar sand 10. The fracture 44 may intersect the fracture 42, but such intersection is not essential to the process of this invention. With this arrangement, the portion of the tar sand between the fractures 42 and 44 is heated, and because of the large overlapping area of the fractures 44 and 42, resistance to flow into the fracture 42 is low.

The tar sand 10 within about one foot and preferably within about three feet of the fracture 44 is heated to a temperature not less than about 200° F., depending on the characteristics of the oil, for a radial distance of about 70 to 80 percent of the distance from the injection well to the production well in a period of one to three weeks, and preferably in a period of one to two weeks. During the period of heating the fracture and a zone above and below it, the injection pressure is maintained high enough to support the overburden and thereby hold the fracture open. An indication of the extent of the heating that has been accomplished will be obtained from the temperature of gases that break through into the production well. It is imperative that the heating of the tar sand adjacent fracture 44 be obtained by a very high rate of flow of hot gases into fracture 44 to obtain a substantially uniform flow pattern from the injection well to cause flow of oil through the formation to each of the production wells. It has been found that a low rate of injection of hot gases into the fracture will result in initial migration of hot gases preferentially to one of the production wells because of non-uniformity of the fracture. The heating of the fracture faces and tar sand by those gases further reduces the resistance to flow through the tar sand and results in channeling of the hot gases to one of the production wells, preferentially to the outer wells. High rates of injection greatly diminish the tendency to channel to one well.

The heating of the tar sand adjacent fracture 44 can be accomplished by burning a fuel such as lease gas, propane, gas oil, etc. supplied through supply line 26 to the burner 20 adjacent the intersection of the fracture 44 with well 12. The temperature of the gases displaced into the fracture can be controlled by the inert gas, water, or air delivered into the well through line 30. If inert gases or water are introduced through line 30 for the desired temperature control, the injection gas temperature should be 400° to 1200° F. If excess air is used to control the temperature of the hot gases, the maximum gas temperature should be no higher than 700° F., and preferably about 400° F., to prevent migration of air into the upper portion of the tar sand adjacent the injection well, with the consequent liberation of heat by burning oil present in the tar sand. The burning of oil in upper regions of the tar sand at this stage is to be avoided because it is imperative to restrict the heating of the tar sand to a thin zone adjacent the fracture in order to obtain the breakthrough of heat extending from the injection well to the production well.

Extremely high rates of flow of hot gases into the fracture 44 are essential in this step. The minimum rate of displacing hot gas into the fracture at the injection well can be calculated from the formula $Q=1400L^2$

when Q is the volume of gas in standard cubic feet per day and L is the distance between injection well and production well in feet. For example, if the well spacing in a five-spot pattern is 250 feet and the temperature of the gases injected into the fracture is 675° F., a rate of flow of the gases of approximately 100,000,000 std. cu. ft. per day is required to obtain the desired heat distribution in a 14-day period. The heating of fracture 42 and fracture 44 can be accomplished simultaneously. Such a procedure has the advantage of reducing heat losses from the tar sand adjacent fracture 42 while fracture 44 is heated, and it is preferred if adequate compressor capacity is available.

If the upper portion of formation 10 adjacent well 12 is heated excessively during the period of heating the faces of the fracture 44, the fracture tends to migrate upwardly during the heating. Air subsequently injected may then flow across the top of the formation and bypass the oil in the formation. Excessive heating of the upper part of formation 10 near well 12 can be avoided by causing combustion of the fuel used to supply the heat to occur in the fracture at some distance from well 12, in which event burner 20 is not required. A pyrophoric liquid such as triethylborane is displaced outwardly into the fracture with an inert fluid such as diesel oil. A fuel-air mixture is then injected into the fracture. Contact of the air with the pyrophoric liquid will cause ignition of the pyrophoric material followed by ignition of the fuel. Adjustment of the composition of the fuel-air mixture and the rate of injection of the mixture into the fracture prevents burning back to the well. For example, if propane is used as the fuel, a fuel-air ratio of about 4-12 percent of the stoichiometric ratio will prevent burning back to the well. Injection of the fuel-air mixture is continued to heat the formation adjacent fracture 44 to the desired temperature.

When the tar sand within about three feet of the fracture 44 has been heated to a temperature of 200° to 400° F. for a distance of about 70 to 80 percent of the distance between the injection well and production well, fuel injection into the injection well 12 is stopped, but the air injection is continued. At this time, the rate of the injection of the air may be reduced. It is only essential that the rate be high enough to maintain combustion and overcome losses of heat from the heated zone adjacent the fractures 44 and 42. Because of the difference in density of the air and the oil in the tar sand, air injected into the fracture migrates upwardly into the tar sand 10 and burns a portion of the oil in the tar sand at some distance from the fracture 42. The heat released by combustion of a portion of the tar sand raises the temperature of the tar sand and thereby increases the mobility of the oil remaining in the heated portion. The oil is driven through the tar sand into fracture 44 and is driven outwardly in fracture 44 to the portion of that fracture overlapping fracture 42. The combination of the large overlapping area of the fractures and the preheating of the intervening portion of the pay zone allows the oil to move into fracture 42 and through that fracture to the production well 14.

Because the oil flowing into fracture 42 is hot, it does not cool the fracture and will supply whatever heat necessary to replace the gradual loss of heat from the formation adjacent fracture 42. However, unless fracture 42 is preheated, the heated oils flowing into it are rapidly cooled to a temperature at which they become highly viscous and quickly plug the fracture. In field tests, fractures opened all of the way between an injection well and certain production wells have become plugged by cold oil during the combustion step; however, once production of hot oil was obtained, no further plugging of the fracture was experienced.

Upon continued injection of air into the fracture 42, the air migrates upwardly into the formation because of the density difference between the air and oil. The air

burns oil draining through the tar sand and releases heat which gradually raises the boundary of the heated zone until the tar sand is heated substantially all of the way to its upper boundary. For purposes of illustration, the boundary of the heated zone at an intermediate period in the production of oil from the tar sand is illustrated in FIGURE 2 by line 46. The heating of the tar sand with the consequent removal of immobile oil from it, the dehydration of clays that may be present, and the spalling of the rock increases the permeability of the tar sand adjacent the injection well. As a result, the fracture adjacent the injection well closes, and thereby further increases the tendency of the injected gases to flow upwardly into the tar sand to cause a more uniform flow of injected gases through the full thickness of the tar sand. The low permeability of the portion of the tar sand 10 to the right of line 46 in FIGURE 2 results in a substantial difference in pressure in that portion of the tar sand and the outer portion of fracture 44; hence, the outer portion of fracture 44 remains open and provides a channel for the flow of oil through the tar sand beyond the combustion front.

In a specific embodiment of this invention, four production wells are drilled at the corners of a five-spot pattern with spacing of 250 feet between the wells into a tar sand at a depth of 200 feet, having a thickness of 24 feet, a porosity of 22 percent, and an air permeability of about 2,000 millidarcys. Horizontal fractures are created in each of the wells four feet above the lower boundary of the tar sand and are propped open with 4 to 8 mesh sand. Burners are installed in diagonally opposite wells adjacent the intersection of the fracture with the borehole of the wells and propane burned at a rate and with excess air to displace 10,000,000 std. cu. ft. per day of combustion products at a temperature of 675° F. into the fractures. The heating of the fractures is continued for 14 days. Thereafter, the burners are transferred to the other two production wells and the procedure repeated for a second 14-day period.

An injection well is drilled through the tar sand at the center of the five-spot pattern and a substantially horizontal fracture is created in the tar sand about five feet above its lower boundary. The fracture is extended from the injection well by the displacement of an aqueous fracturing liquid free of propping agent and containing about one pound per gallon of a gelling agent approximately 80 percent of the distance to the production wells. A burner is run into the injection well to a position opposite the fracture. Air and propane gas are displaced down the well and burned adjacent the fracture, and the hot combustion products displaced into the fracture. Water is displaced down the well at a rate to cool the products of combustion to a temperature of approximately 900° F. The injection of the propane, air, and water is controlled to produce a flow rate of 100,000,000 std. cu. ft. per day of gas at a temperature of approximately 900° F. into the fracture. The heating of the fracture extending from the injection well is continued for 14 days.

After heating the fracture communicating with the injection well for fourteen days, the fuel supply and cooling water are stopped and air injection is continued at a reduced rate of approximately 500,000 std. cu. ft. per day. Oil in the formation is burned which heats other oil that travels radially outward from the injection well to the fractures communicating with the production well and through those fractures to the production well. The rate of injection of air into the injection well is controlled to maintain less than 5 percent oxygen in the gases discharged from the production well. If the oxygen concentration rises above 5 percent, the rate of injection of the air is decreased.

In a test of the foregoing process, it was found that an oil having a viscosity of 50,000 centipoises at 70° F. was upgraded to an oil having a viscosity at 70° F. of

1500 centipoises. Such oil has a viscosity of approximately 20 to 30 centipoises at 200° F., and the viscosity is further reduced by the dispersion of CO₂ in it. The ratio of air injected to produce oil was 28,000 std. cu. ft. per barrel. The produced oil was suitable for use as No. 6 fuel oil without further processing.

We claim:

1. A method of recovering an oil of low mobility from an oil-bearing formation containing said oil penetrated by a production well and an injection well comprising creating a substantially horizontal fracture extending from the production well into the oil-bearing formation near the lower boundary thereof, depositing a heat resistant propping agent in the fracture, displacing via the production well a hot gas at a temperature of 400° F. to 1200° F. into the fracture at a high rate to heat the formation within one foot of the fracture to a temperature of at least 200° F. in a period of less than about 14 days, creating a second fracture extending from the injection well substantially horizontally into the oil-bearing formation near the lower boundary thereof, displacing a hot gas at a temperature of 400° to 1200° F. via the injection well into the second fracture at a high rate to heat the formation within three feet of the fracture to a temperature of at least 200° F. in a period of less than about 21 days, discontinuing displacement of hot gas into the fractures, displacing oxygen-containing gas via the injection well into the second fracture, igniting oil in the formation adjacent the injection well, and continuing the injection of oxygen-containing gas via the injection well into the second fracture to cause combustion of oil in the formation to heat oil to a temperature at which it flows through the first fracture into the production well, and lifting oil from the production well.

2. A method of recovering an oil of low mobility from an oil-bearing formation containing said oil, said oil-bearing formation being penetrated by an injection well and a production well spaced therefrom, comprising creating a substantially horizontal first fracture extending from the production well into the oil-bearing formation near the lower boundary thereof, depositing a heat-resistant propping agent in the fracture, displacing via the production well and into the fracture a hot gas at a rate of at least $155 L^2$ std. cu. ft. per day where L is the distance in feet between the injection well and production well and a temperature of 400° to 1200° F. to heat the oil-bearing formation within three feet of the fracture to a temperature of at least 200° F., creating a second fracture extending from the injection well substantially horizontally into the oil-bearing formation near the lower boundary thereof, displacing via the injection well a gas at a temperature of 400° to 1200° F. and a rate of at least 1400 L^2 std. cu. ft. per day into the second fracture to heat the oil-bearing formation within three feet of the second fracture to a temperature of at least 200° F., said second fracture being free of propping agent, discontinuing the displacement of hot gas into the fractures, displacing via the injection well an oxygen-containing gas into the second fracture, igniting oil in the formation adjacent the injection well and continuing the injection of oxygen-containing gas via the injection well into the second fracture to cause combustion of oil in the formation and thereby heat oil in the oil-bearing formation to a temperature at which it flows to the first fracture and through the first fracture to the production well, and lifting oil from the production well to the surface.

3. A method of recovering an oil of low mobility from an oil-bearing formation containing said oil, said oil-bearing formation being penetrated by an injection well and a production well spaced therefrom, comprising creating a substantially horizontal first fracture extending from the production well into the oil-bearing formation near the lower boundary thereof, depositing a heat-resistant propping agent in the fracture, displacing via the production well and into the fracture a hot gas at a rate of at

least $155 L^2$ std. cu. ft. per day where L is the distance in feet between the injection well and production well and a temperature of 400° to 700° F. to heat the oil-bearing formation within three feet of the fracture to a temperature of at least 200° F., creating a second fracture extending from the injection well substantially horizontally into the oil-bearing formation near the lower boundary thereof, displacing via the injection well a gas at a temperature of 400° to 700° F. and a rate of at least $1400 L^2$ std. cu. ft. per day into the second fracture to heat the oil-bearing formation within three feet of the second fracture to a temperature of at least 200° F., said second fracture being free of propping agent, discontinuing the displacement of hot gas into the fractures, displacing via the injection well an oxygen-containing gas into the second fracture, igniting oil in the formation adjacent the injection well and continuing the injection of oxygen-containing gas via the injection well into the second fracture to cause combustion of oil in the formation and thereby heat oil in the oil-bearing formation to a temperature at which it flows to the first fracture and through the first fracture to the production well, and lifting oil from the production well to the surface.

4. A method of recovering an oil of low mobility from an oil-bearing formation containing said oil penetrated by a production well and an injection well comprising creating a substantially horizontal fracture extending from the production well into the oil-bearing formation near the lower boundary thereof, depositing a heat-resistant propping agent in the fracture, displacing via the production well a hot gas at a temperature of 400° F. to 1200° F. into the fracture at a high rate to heat the formation within one foot of the fracture to a temperature of at least 200° F., discontinuing the displacement of hot gas via the production well into the fracture, creating a second fracture extending from the injection well substantially horizontally into the oil-bearing formation near the lower boundary thereof, displacing via the injection well a mixture of a fuel and oxygen-containing gas into the second fracture, igniting the mixture of fuel and oxygen-containing gas and burning the fuel in the second fracture to heat the oil-burning formation within three feet of the second fracture to a temperature at least 200° F., discontinuing the displacement of fuel into the second fracture, continuing the injection of oxygen-containing gas via the injection well into the second fracture to cause combustion of oil in the formation to heat oil to a temperature at which it flows through the first fracture into the production well, and lifting oil from the production well.

5. A method of recovering an oil of low mobility from an underground oil-bearing formation containing said oil, said oil-bearing formation being penetrated by a produc-

tion well and an injection well spaced therefrom, comprising creating a substantially horizontal first fracture extending from the production well into the oil-bearing formation near the lower boundary thereof for a distance of at least about 20 percent of the distance to the injection well, depositing sand in the first fracture to prop the fracture open, burning a fuel in the borehole of the production well adjacent the first fracture to produce hot combustion gases, diluting the hot combustion gases with a non-combustible gas to form a mixture of gases at a temperature in the range of 400° to 1200° F., displacing said mixture of gases into the first fracture at a rate of at least $155 L^2$ std. cu. ft. per day where L is the distance in feet between the injection and production wells for a period of about 14 days to heat the oil-bearing formation within three feet of the fracture to a temperature of at least 200° F., creating a second fracture extending from the injection well substantially horizontally into the oil-bearing formation near the lower boundary thereof for a distance of at least about 80 percent of the distance from the injection well to the production well, injecting at a rate of at least $1400 L^2$ std. cu. ft. per day via the injection well and into the second fracture hot gases at a temperature of 400° to 1200° F. and a pressure adequate to maintain the second fracture open to heat the formation within three feet of the fracture to a temperature of at least 200° F. in a period less than about three weeks, discontinuing the injection of the hot gases into the fractures, displacing air via the injection well into the second fracture to ignite oil in the formation adjacent the injection well, continuing the injection of air into the second fracture to move a combustion front through the oil-bearing formation from the vicinity of the injection well toward the production well whereby the second fracture closes behind the combustion front, and lifting oil through the production well.

6. A method as set forth in claim 5 in which the injection and production wells are located in a five-spot pattern with the production wells at the corners of the five-spot pattern.

UNITED STATES PATENT OFFICE
CERTIFICATE OF CORRECTION

Patent No. 3,159,216

December 1, 1964

Ronald L. Reed et al.

It is hereby certified that error appears in the above numbered patent requiring correction and that the said Letters Patent should read as corrected below.

Column 1, line 20, for "coil" read -- oil --; column 9, line 42, for "oil-burning" read -- oil-bearing --.

Signed and sealed this 20th day of April 1965.
